THREE-PORT CONNECTOR BLOCK

Charles H. Graham, Mountain View, Calif., assignor to
Gra-Tec, Inc., Los Altos, Calif.

Filed Oct. 24, 1966, Ser. No. 4,427

Term of patent 14 years

(Cl. D91—3)

FIG.1

FIG.2

FIG.3

FIG.4

FIG.5

FIGURE 1 is a perspective view of the three-port connector block embodying my design;

FIGURE 2 is a top plan view of the connector block shown in FIGURE 1, the bottom view being a mirror image thereof;

FIGURE 3 is a front elevational view of the block shown in FIGURE 2, taken along line 3—3 in the direction of the arrows;

FIGURE 4 is a back elevational view of the connector block shown in FIGURE 2, taken along line 4—4 in the direction of the arrows; and

FIGURE 5 is a side elevational view of the connector block shown in FIGURE 2, taken along line 5—5 in the direction of the arrows.

I claim:

The ornamental design for a three-port connector block, as shown and described.
